FIG. 3.

FIG. 4.

INVENTOR:
Louis C. Mark

BY

Louis B. Goldham

ATTORNEY.

UNITED STATES PATENT OFFICE

2,239,009

LOCKET

Louis C. Mark, Providence, R. I.

Application October 1, 1940, Serial No. 359,199

8 Claims. (Cl. 63—19)

My invention relates to improvements in lockets adaptable as pendants or charms for chains and containing a casing for pictures or other keep-sakes, and the objects of my improvements are to attain the things commonly sought in such articles, including a construction which obviates the objections to the hinged or snap covers with which such locket containers are usually provided, renders said containers conveniently severable from their encasements, and provides a locket which shall be simple in construction and economical to manufacture and strong and durable in use. A further object of my improvement is to provide a novel construction of locket having a double faced container, the parts being so constructed and arranged that the locket shall be artistic and ornamental and also compact.

I attain these objects by means of a novel construction, combination, and arrangement of parts hereinafter fully described and claimed, and illustrated in the accompanying drawing, forming part of this specification, in which

Fig. 1 is a view in perspective of the locket as it appears in closed position;

Fig. 2 a plan view of the locket as it appears when opened;

Fig. 3 a section on the line 3—3 of Fig. 4;

Fig. 4 a section on the line 4—4 of Fig. 3.

Similar numerals refer to similar parts throughout the several views.

In the accompanying drawing I show my invention as embodied in a locket of simple, flat circular shape for simplicity and convenience of illustration, it being understood that the configuration of the locket forms no part of my present invention and that I do not limit myself in this respect, the essential features of my invention being the mechanical structure of the container and its incasement, specifically as hereinafter indicated.

My invention comprises a keepsake container in the form of a disc or plate 1 of any desired external configuration, having a flange 2 around its periphery to provide a seat for a picture or other keepsake 2a, connected at a point near its periphery, by a hinge 3 having a pin 4 serving as a pivot, to a point near the periphery of a second keepsake container comprising a disc or plate 5 of the same external configuration as the disc or plate 1, the disc or plate 5 having a flange 6 around its periphery to provide a seat for a picture or other keepsake 5a. A spring 7 is coiled around the pin 4 in such manner that the disc or plate 1 will be automatically distended outward on the axis of the pin 4 from the disc or plate 5

when the said discs or plates are disengaged from the aperture or recess formed by the cover members of the incasement or body hereinafter described, as shown in Fig. 2.

Preferably, the disc or plate 5 should be somewhat larger than the disc or plate 1 so that when the latter is folded inward on the axis of the pin 4, and thereby superposed on the disc or plate 5, it will lie wholly within the inner face of the disc or plate 5, as shown in Fig. 4.

The disc or plate 5 is provided with an integral arm or tongue 8 on its periphery, positioned some distance from the hinge 3, which arm is pivoted by a pin or rivet 9 between the plates 10 and 11 of the incasement or locket body, at a point near the periphery of said body. The front plate 10 and the rear plate 11 may be of any desired external configuration which will permit the discs or plates 1 and 5 to be wholly concealed in the edge aperture or recess between their respective surfaces when the locket is in closed position, as shown in Fig. 4.

Diametrically opposite the pivot 9 on the periphery of the disc or plate 5 is positioned an integrally formed finger engaging lug 12 so dimensioned that it will extend beyond the encasing discs or plates when the locket is in closed position, to facilitate opening the locket for inspection.

Between the incasement disc or plates 10 and 11, extending from a point at their periphery adjacent to the tongue or arm 8 but at a distance therefrom sufficient to permit the said tongue or arm to rotate on the pivot 9 and extend the discs or plates 1 and 5 as shown in Fig. 2, to a point somewhat less than half the distance around the periphery of the incasement discs or plates, is positioned a narrow strip 13, of sufficient thickness to form an edge aperture or recess between the said incasement discs or plates which will permit rotation of the discs or plates 1 and 5 on the fulcrum of the pivot arm or tongue 8 to the closed position as shown in Fig. 3. The said incasement discs or plates may be secured to the strip 13 by rivets 14, 15 and 16, or by other suitable means.

At a point on the periphery of the incasing members, preferably on the strip 13 adjacent the lug 12, is positioned a ring 17 by which the entire locket may be suspended from a chain or other article. The said ring may be secured to the rivet 16 as shown in Fig. 4, or may be secured in any other suitable manner.

The locket thus constructed is thin and compact and may be suspended from a chain or may

be carried in the pocket or purse. When it is desired to have access to the locket, the finger is engaged with the lug 12 and downward or outward movement is imparted to the enclosed containers. The latter swing upon the pivot 9 until the nested or telescoped plates 1 and 5 clear the body, whereupon the spring 7 causes the keepsake container parts to swing to open or extended position. To close the locket, it is but necessary to swing the plates 1 and 5 together and move them inwardly of the locket case or body; the spaced plates of the latter holding the keepsake container together. The spring 7 exerts outward pressure upon the plates 1 and 5, which causes sufficient frictional contact between the said plates and the case or body to retain the nested containers in closed position and against accidental or casual opening.

Having thus fully described my invention, what I claim as new and desire to secure by Letters Patent is:

1. In a locket, the combination of an incasement formed with an edge aperture, a keepsake container having a tongue or arm on its periphery pivotally secured to the edge of said incasement, and a second keepsake container hingedly secured to the first keepsake container.

2. In a locket, the combination of an incasement formed with an edge aperture and having a suspender loop, a keepsake container having a tongue or arm on its periphery pivotally secured near the periphery of said incasement, a second keepsake container hingedly secured to the first keepsake container, and means for distending the second from the first keepsake container on the fulcrum of the said hinge.

3. In a locket, the combination of an incasement formed with an edge aperture and having a suspender loop, a keepsake container having a tongue or arm on its periphery pivotally secured near the periphery of said incasement and adapted to be inserted into and removed from said incasement through said aperture in alignment with the main plane of said incasement on the fulcrum of the said pivot, and a second keepsake container hingedly secured to the first keepsake container having a spring coiled around said hinge for distending the second from the first keepsake container on the fulcrum of the said hinge.

4. In a locket, the combination of an incasement formed with an edge aperture and having a suspender loop, a keepsake container having a tongue or arm on its periphery pivotally secured near the periphery of said incasement and adapted to be inserted into and removed from said incasement through said aperture in alignment with the main plane of said incasement on the fulcrum of the said pivot, said keepsake container having finger engaging means positioned integrally its periphery to facilitate opening the locket, and a second keepsake container hingedly secured to the first keepsake container having a spring coiled around said hinge for distending the second from the first keepsake container on the fulcrum of the said hinge.

5. In a locket, the combination of an exterior casing provided with front and rear plates held apart by a peripheral strip, said exterior casing being formed with an edge aperture and having a suspender loop, a keepsake container having a tongue or arm formed integrally on its periphery pivotally secured on said exterior casing near its periphery and adapted to be inserted into and removed from said exterior casing through such edge aperture in alignment with the main plane of said exterior casing on the fulcrum of the said pivot, said keepsake container having finger engaging means formed integrally on its periphery, a second keepsake container hingedly secured to the first keepsake container and adapted to be superposed contiguous to and within the inner face of the first keepsake container, and having a spring coiled around said hinge for distending the second from the first keepsake container on the fulcrum of the said hinge.

6. In a locket, the combination of an exterior casing consisting of front and rear plates held by a relatively narrow strip extending about half way around the periphery of said exterior casing and having a suspender loop integrally formed on the edge of said strip, a keepsake container having a tongue or arm on its periphery pivotally secured to said exterior casing at a point near its periphery and adjacent one end of said strip and adapted to be inserted into and removed from said exterior casing through the edge aperture formed by the said exterior casing and strip in alignment with the main plane of said exterior casing on the fulcrum of the said pivot, said keepsake container having finger engaging means integral its periphery to facilitate opening the locket, a second keepsake container hingedly secured to the first keepsake container having a spring coil around said hinge for distending the second from the first keepsake container on the fulcrum of the said hinge, said second keepsake container being somewhat smaller than the first keepsake container and thereby adapted for superposition within the keepsake-retaining flange of the first keepsake container.

7. In a locket, an incasement comprising a body having an edge aperture, a keepsake container pivoted within said body and movable into and out of the latter through said aperture, and a second keepsake container hingedly connected to said first named keepsake container, and movable in a plane at right angles to the direction of movement of the said first keepsake container.

8. In a locket, an incasement comprising a flat hollow body having an edge aperture, a keepsake container pivoted within said body and movable into and out of the latter through said aperture, a second keepsake container hinged to the first keepsake container for swinging movement in a direction at right angles to the plane of movement of the first keepsake container, and a spring tending to move said keepsake containers apart.
